Term of patent 14 years

Int. Cl. D15—07; D7—06

U.S. Cl. D49—1

FIGURE 1 is a front elevation view of a dishwasher control panel embodying my new design;

FIGURE 2 is a perspective view of the control panel shown in FIGURE 1;

FIGURE 3 is a sectional view of the control panel of FIGURE 1 taken along line 3—3 thereof;

The dominant features of my design reside in the portions shown in full lines.

The dishwasher is fragmentarily shown in broken lines in FIGS. 1 and 2 for illustrative purposes only.

I claim:

The ornamental design for a dishwasher control panel, substantially as shown and described.
